UNITED STATES PATENT OFFICE.

GUSTAV A. RAKOWSKY, OF DULUTH, MINNESOTA, ASSIGNOR OF ONE-HALF TO I. K. LEWIS, OF DULUTH, MINNESOTA.

SIDE-DUMP CAR.

1,066,527.

Specification of Letters Patent.

Patented July 8, 1913.

Application filed August 12, 1911. Serial No. 643,664.

To all whom it may concern:

Be it known that I, GUSTAV A. RAKOWSKY, of Duluth, St. Louis county, Minnesota, have invented certain new and useful Im-
5 provements in Side-Dump Cars, of which the following is a specification.

My invention relates to dump cars for transporting commodities of different kinds and particularly ore, and the object of the
10 invention is to provide a car which, when tilted to discharge its contents, will have an entirely unobstructed discharge opening.

A further object is to provide side gates which will in no way interfere with the dis-
15 charge of the load from the car.

A further object is to provide means which will positively prevent the car from tilting toward the operator and dumping the contents of the car upon him.

20 Other objects of the invention will appear from the following detailed description.

The invention consists generally in various constructions and combinations, all as hereinafter described and particularly pointed
25 out in the claims.

In the accompanying drawings forming part of this specification, Figure 1 is an end elevation of a car embodying my invention, Fig. 2 is a similar view showing the car tilted, Fig. 3 is a detail view of the device for locking the car body, Fig. 4 is a side elevation of the car.

In the drawings, 2 represents the truck frame, 3 a series of standards or pedestals
30 mounted at suitable intervals along the center line of the car and 4 the car body, pivotally supported on the pedestals 3 at pivotal points 5, there being a suitable number of these points according to the capacity of
35 the car.

The sides of the car body are open, to allow it to discharge its contents upon either side of the car, and gates are hinged at 6 on each side of the car body, consisting of
40 plates 7 which close the discharge openings and have end wings 8 which lap by the ends of the car body on each side and at each end of the car. When the gates are tilted outwardly the plates 7 form continuations
45 of the bottom of the car body while the wings 8 will form continuations of the end

walls thereof, thereby guiding and directing the material discharged from the car body away from the truck frame and wheels, and to a considerable distance from the track. The gates operate quickly, moving faster than the tilting body by means of the mechanism hereinafter described, so that under all circumstances the openings at the sides of the car will be unobstructed, 60 the gates tilting on their hinges ahead of the material so that no matter how quickly the car body may be tilted, the gates will in no way obstruct the flow of the material therefrom. For the purpose of controlling the movement of these gates and the tilting of the car I provide rock shafts 9 mounted in bearings 10 upon each side of the car, lengthwise thereof. Each of these shafts has an operating lever 10', preferably 70 mounted about midway of the shaft. At suitable intervals on the shaft struts 11 are arranged, having anti-friction rollers 12 at their upper ends which bear on the floor of the car body 4 and support it securely 75 against premature tilting. Bars 13 are pivotally connected at one end with the upper portions of the struts 11 and extend transversely of the car and are connected to arms 14 mounted on the rock shafts 9. These 80 arms may be secured to the rock shafts by any suitable means, and the rock shafts may be made polygonal in cross section to prevent the arms from turning thereon. When the arms and the bars are in line with one another, as indicated in Fig. 1, they will form a toggle mechanism which will hold the upright struts at the other side of the car rigidly in their locking position, and as the bars attached to the struts on one side 85 of the car are connected to the rock shaft on the opposite side of the car it follows that it will be impossible for the operator to dump the contents of the car upon himself. As soon as the struts are removed from one 90 side of the car the load in the car will cause the body to tilt toward that side assuming that the greater portion of the load is on that side of the body pivot, and at that time the gate on that side of the car will be 100 opened by the mechanism which I will now proceed to describe in detail.

Bars 15 are pivotally connected at one end to the wings 8 of the gate on one side of the car and extending across the car are pivotally connected at their opposite ends 5 to the lower ends of links 16 whose upper ends are pivotally connected to the wings 8 on that side of the car. The pivot pins 17 connecting the bars 15 and the links 16 are extending beyond the links and bars and are 10 adapted to fit into seats 18 provided in castings 19 that are mounted on the truck frame. Pins 20 are slideable in sockets in the castings 19 and are adapted to move inwardly over the pins 17 and lock them in the seats 15 18. The outer ends of the pins 20 have loops 21 thereon to receive arms 22 mounted on the rock shafts so that when the shafts are rocked the pins 20 at a predetermined point in the movement of the arms will be 20 actuated to release the pins 17 and allow the gate on the opposite side of the car to swing outwardly as the car body tilts with the removal of the support on that side of the car. This movement is indicated plainly 25 in Fig. 2, where the bar 15 and the link 16 are shown released from the casting 19 and swinging upwardly to allow one of the gates to assume its open position. At the same time, as the car body tilts, the links attached 30 to the opening gate will limit its tilting movement, as indicated in Fig. 2, though permitting it to swing to a point where it will be entirely out of the path of the material flowing from the car before the tilting 35 of the car body is checked. At the same time that the bars 15 and the links 16 are released by the rocking of the shaft, the supports on one side of the car will be withdrawn so that the car body can tilt away 40 from the operator and discharge its contents. When the car dumps, the bars 15 attached to the gate on that side of the car in which the operator is stationed hold the gate on that side in place and prevent the load in 45 the car from shoving the gate outwardly before the car dumps. As the car body tilts, the gate on the dumping side will swing outwardly and the bars connected with the gate being released at their inner ends, the 50 gate will move faster than the car body and assume the position indicated by full lines in Fig. 2 when the car body reaches its dumping position. The gate will thus form an inclined continuation of the floor of the 55 car body and in no way retard the discharge of the material from the car. When the material has been discharged, the car body may be swung back to its normal horizontal position. The closing of the gate is caused 60 by the car body coming to its normal position. In case the upright supports or struts should get out of order the bars attached to the gates will prevent them from tilting until repairs have been made. In some

instances it may be desirable to carry other material than ore and I may release the locking bars and links allowing them to assume the position shown by dotted lines in Fig. 1, so that the gates will drop to form horizontal continuations of the car floor; 70 then upon releasing the supports the car body may be tilted in either direction, as desired. In other respects the operation of the car is substantially as heretofore described. 75

I claim as my invention:—

1. The combination, with a truck frame, of a car body centrally pivoted thereon and having open sides, pivoted gates for closing said open sides, means for locking said car body against premature tilting, means for holding said gates in their closed position, and means arranged to release said locking and said holding means to allow the car body to tilt to one side and allow the gate on that side to swing to its open or dumping position. 80

2. The combination, with a truck frame, of a car body centrally pivoted thereon and having open sides, gates pivoted on said car body and normally closing said open sides, supports for locking said car body against premature tilting, means for holding said gates in their closed position, and means for releasing said car body to tilt toward one 90 side and tripping the holding means for the gate on that side to allow the car and gate to swing to their dumping position. 95

3. The combination, with a car truck, of a car body centrally pivoted thereon and having open sides, gates pivoted on the floor of the car body and adapted to close said open sides and swing to a dumping position to form a continuation of the floor of said car body, means for locking said car 100 body in a horizontal position, means for holding said gates in their closed position, and means for releasing said locking means to allow the car body to tilt to one side and tripping said holding means to allow the 110 gate on that side to swing to a dumping position. 105

4. The combination, with a truck frame, of a car body centrally pivoted thereon and having open sides, gates normally closing 115 said open sides, rock shafts mounted on said truck frame, struts mounted on said rock shafts and adapted to swing to an upright position beneath said car body, arms secured to said rock shafts, bars pivotally connecting said arms on one side of the car with the struts on the opposite side of the car, said bars and arms forming a toggle connection between said struts and shafts, and means for rocking said shafts to release said 120 struts or lock them in their upright position. 125

5. The combination, with a truck frame, of a car body centrally pivoted thereon and

adapted to tilt to either side, means for locking said car body against premature tilting, gates arranged to close the sides of said car body, bars pivotally connected at one end 5 with the gate on one side of the car, links pivotally connected with the other ends of said bars and with the gate on the other side of the car, means for locking the pivotal connections of said bars and links to hold 10 said gates against premature tilting, means for tripping the lock for said car body and means for releasing the pivotal connections of said bars and links to allow the simultaneous tilting of said car body and the opening 15 of said gate.

6. The combination, with a truck frame, of a car body centrally mounted thereon and adapted to tilt toward either side, gates pivoted on said car body, means for normally locking said car body against premature movement, bars pivotally connected with the gates on both sides of the car and extending diagonally across the car, links pivotally connected with both of said gates near the pivots of said bars and also pivotally connected with said bars on opposite sides of the car, means for locking the pivotal connections of said bars and links against premature movement, the release of the bars and links on one side of the car allowing the gate to open on the opposite side of the car, and the links connected with said last named gate limiting its opening movement.

35 7. The combination, with a truck frame, of a car body centrally mounted thereon and having open sides and adapted to tilt toward either side of the car, gates pivoted on said car body, bars pivotally connected with said gates and extending diagonally across the car, links pivotally connected with said gates and also having pivotal connections with said bars, means mounted on the truck frame and having seats for the pivot pins connecting said bars and links, means for locking said pins in said seats, means for locking said car against premature tilting movement, means for releasing said locking means and said pivot pins to allow the 50 car body to tilt and the gates to swing open.

55 8. The combination, with a truck frame of a car body centrally pivoted thereon and adapted to tilt toward either side of the car, gates mounted on said car body, rock shafts mounted on said truck frame, means actuated by the movement of said rock shafts for locking said car body in its horizontal position or releasing it, means pivotally connecting the gate on one side of said car with the gate on the opposite side thereof, means for locking said pivotal connection to hold said gates in their closed position, and means actuated by the rocking of said shafts

for releasing said locking means to allow 65
said gates to swing to an open position.

9. The combination, with a truck frame, of a car body centrally pivoted thereon and adapted to dump to either side of the car, gates for said car body, means for locking 70 said car body against premature tilting, means operatively connecting the gate on one side of said car body with the gate on the other side thereof, means for locking 75 said gates in their closed position and means for tripping said car body locking means and said gate locking means.

10. The combination, with a truck frame, of a car body centrally mounted thereon and adapted to tilt toward either side, gates for 80 said car body, means for locking said car body against premature tilting, means operatively connecting the gate on one side of the car body with the gate on the other side of the car body, means for locking said gates 85 against premature tilting, and means located on one side of the car for releasing the gate on the opposite side of the car.

11. The combination, with a car truck, of a car body centrally pivoted thereto and 90 having open sides, gates pivotally connected with the floor of said car body and having end wings adapted to lap by the end walls of the car body, said gates, when swung to a vertical position, closing the open sides of 95 the car and when swung to a dumping position forming a continuation of the floor of the car, and said end wings preventing the discharge of the material at the ends of said gates, means for locking said car body in a 100 horizontal position, means for holding said gates in their closed position, and means for tripping said locking means and releasing said holding means.

12. The combination, with a truck frame, 105
of a car body mounted thereon and adapted
to tilt toward either side, gates for said
body, means operatively connecting the gate
on one side of the car body with the gate
on the other side of the car body, means for 110
locking said gates against premature move-
ment, and means operable on one side of the
car for releasing the gate on the opposite
side of the car.

13. The combination, with a truck frame, 115
of a car body centrally pivoted thereon and
adapted to tilt toward either side, gates
pivoted on said car body, bars pivotally con-
nected at one end with the gate on one side
of the car, links pivotally connected with the 120
gate on the other side of the car and also
pivotally connected with said bars, said bars
and links swinging upon their pivots to al-
low the gate on one side of the car to swing 125
to an open position when the car body is
tilted toward that side, and means for nor-
mally locking said bars and links against
premature movement. 126

14. The combination, with a truck frame, of a car body centrally pivoted thereon and adapted to tilt toward either side, gates pivoted to said car body on each side thereof and normally closing the discharge openings therein, a toggle mechanism pivotally connecting the gate on one side of the car body with the gate on the opposite side of the car body, and means located below the car body

for locking said toggle mechanism and preventing premature movement of said gates. 10

In witness whereof, I have hereunto set my hand this 28 day of July, 1911.

GUSTAV A. RAKOWSKY.
